(57) **CLAIM**

The ornamental design for a cup lid, substantially as shown and described.

DESCRIPTION

FIG. 1 is a perspective view of the cup lid, with the reclosable spout of the cup lid being shown in the open position.

FIG. 2 is a perspective view of the cup lid of FIG. 1, with the reclosable spout of the cup lid being shown in the closed position.

FIG. 3 is a plan view of the cup lid of FIG. 1.

FIG. 4 is a front elevation view of the cup lid of FIG. 3; and, FIG. 5 is a front perspective view of the cup lid of FIG. 2. The broken lines shown in all views are for illustrative purposes only and form no part of the claimed design.
